UNITED STATES PATENT OFFICE

EURETTA L. KIP, OF BROOKLYN, NEW YORK

SWEATBAND

Application filed September 27, 1930. Serial No. 484,729.

This invention relates to sweat bands for hats, and has for one of its objects the provision of a sweat band provided with means to prevent perspiration and other oily matter from reaching the hat proper, and so prevent the hat from becoming stained from such causes.

Another object of the invention is to provide a hat sweat band with a perspiration insulating medium secured by one row of stitches to the sweat band, and by a second row of stitches to the hat.

Other objects and advantages will appear as the nature of the improvements is better understood, the invention consisting substantially in the novel arrangement and correlation of parts herein fully described, and illustrated in the accompanying drawings wherein similar reference characters are used to describe corresponding parts throughout the several views, and then finally pointed out and specifically defined and indicated in the appended claim.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which

Figure 1 is a face view of my improved sweat band partly broken away.

Figure 2 is a fragmental sectional view through a hat showing one form of my improved sweat band as secured thereto.

Figure 3 is a fragmental perspective view of a modified form of my invention and

Figure 4 is a similar view of another modified form of the invention.

In the present day method of attaching sweat bands to hats, the sweat band securing thread comes in direct contact with the head of the wearer and the hat, thus providing a direct passage for perspiration from the head of the wearer to the hat causing same to

become stained. In order to obviate this undesirable feature I have perfected my new and improved sweat band.

Referring now to the drawings in detail 5 indicates a sweat band usually made of leather, which is provided near its hat securing edge (see Figures 1 and 2) with an inner strip 6 and an outer strip 7 folded over to form a bead 8 in which is carried a reed 9. The said strips 6 and 7 are secured to the sweat band 5 by means of a row of stitches 10 which pass through the one ply 11 of the outer strip 7 and both plies of the inner strip 6, leaving the ply 12 of the strip 7 unperfected and detached from the inner strip 6. 65

The sweat band may be attached to the hat 15 by means of stitches 16 which pass through the hat material and both plies of each of the strips 6 and 7, but not through the sweat band 5. In this manner the ply 12 acts as an 70 insulator between the hat 15 and the stitches 10, and the sweat band 5 insulates the band securing stitches 16 from coming in contact with the head of the wearer.

The strips 6 and 7 may be made of any suitable material, preferably a material having a rubberized surface. If desired a coating 18 of rubber cement may be applied to the inner surface of the strip 7 so that all of the plies may be made to adhere together after the 80 sweat band is secured to the said strips 6 and 7 and provide a firm base for attaching the sweat band to the hat.

In Figure 3 I have shown a modified form of my invention in which the strips 6 and 7 are secured to the sweat band 5 by a row of stitches 20 passing through plies 21 and 22 respectively and through the sweat band. The remaining plies are glued together but a space is left at the folded edge 23 for the insertion of the reed 9. To secure the assembled sweat band to the hat a row of stitches is passed through all of the plies and the hat material as in the form shown in Figures 1 and 2. 95

In the Figure 4 form of my invention the plies 25 and 26 of the strips 6 and 7 are sewn to the sweat band 5 by a row of stitches 27, the ply 28 of the strip 6 is pasted to the ply 25, the reed 9 is inserted at the folded 100

over portion of the said strip 6 and the assembled sweat band is secured to the hat as in the previously described forms.

From the foregoing it will be seen that I have provided a simple yet efficient sweat band construction that will prevent the sweat band hat securing thread or stitches from coming into contact with the head of the wearer and thus eliminate all danger of staining the hat by any perspiration or oily substance from the hair or head of the wearer.

It will also be seen that the strip securing stitch forming thread is insulated from the hat material, likewise preventing any staining of the hat.

Having described my invention what I claim as new and desire to secure by Letters Patent is:

In combination with a hat, a hat band therefor comprising a main band, a pair of superposed folded over strips secured to the main band by a row of stitches passing through a single ply of the outer strip, both plies of the inner strip, and through the main band, the other ply of the outer strip insulating the said stitches from the hat, and a second row of stitches above the first mentioned row insulated from the head of the wearer by the main band and passing through all of the plies of the superposed strips and the hat material.

In testimony whereof I hereunto affix my signature.

EURETTA L. KIP.
